UNITED STATES PATENT OFFICE.

PAUL HICKISCH, OF DECATUR, ILLINOIS.

DESIGN FOR A FIRE-GRADE FOR OIL-STOVES.

SPECIFICATION forming part of Design No. 12,364, dated July 19, 1881.

Application filed May 23, 1881. Term of patent 3½ years.

To all whom it may concern:

Be it known that I, PAUL HICKISCH, of the city of Decatur, in the county of Macon and State of Illinois, have invented a certain new 5 Design in Fire-Grates Used in Connection with Vapor, Oil, or Gasoline Stoves; and I do hereby declare that the following is a full, clear, and exact description thereof, reference being had to the accompanying drawings, and to the letters of reference marked thereon, which form part of this specification, in which—

Figure 1 is a plan view, and Fig. 2 a cross-section on the line indicated by *y y* in Fig. 1.

The leading feature of my design consists in 15 forming a grate for gasoline or oil stoves with an outer and inner ring, the latter having a sloping or beveled face, and the two connected by ribs, all substantially as shown.

A represents the outer ring, and B the inner 20 ring, which latter is cast with a sloping or beveled face, and also with scallops *a a*. The lower outer edge of the exterior ring is cast or formed

with a rabbet, as seen in Fig. 2. The two rings A B are united by a series of ribs, *b b'*, the ribs *b* projecting some distance toward the center 25 and sloping downward upon their lower sides, while the ribs *b'* extend only to or a little beyond the inner ring.

What I claim, and desire to secure by Letters Patent, is— 30

1. The design for grates herein shown, consisting of outer and inner rings, A B, ribs *b b'*, and scallops *a a*, substantially as set forth.

2. The design for grates herein shown, consisting of the outer and inner rings, A B, the 35 former having ribs *b b'*, and the latter a sloping or beveled face, and scallops *a a*, as described.

In testimony that I claim the foregoing as my own I affix my signature in presence of two witnesses.

PAUL HICKISCH.

Witnesses:

C. H. BROWN,
H. T. MORRISON.
